(57) **CLAIM**

(**) Term: **14 Years**

The ornamental design for a mountain bicycle mono-coque frame, chassis, and suspension, as shown and described.

(21) Appl. No.: **29/130,934**

DESCRIPTION

(22) Filed: **Oct. 10, 2000**

FIG. 1 is a left side elevation view of our present new design of a mountain bicycle mono-coque frame, chassis, and suspension, the classic bicycle parts and components showing in broken lines in FIGS. 1-2 is for illustrative purpose only and forms no part of the present description in our novel ornamental design;

(51) LOC (7) Cl. **12-11**
(52) U.S. Cl. **D12/111**
(58) Field of Search **D12/111; 280/281.1, 280/283-288.3**

FIG. 2 is a right side elevation view thereof;
FIG. 3 is an enlarged front elevation view thereof;
FIG. 4 is an enlarged rear elevation view thereof;
FIG. 5 is a top view thereof; and,
FIG. 6 is a bottom view thereof.

(56) **References Cited**

The broken lines shown are for illustrative purposes only and form no part of the claimed design.
